(57) **CLAIM**

The ornamental design for an automobile grille, as shown and described.

DESCRIPTION

FIG. 1 is a perspective view of the automobile grille thereof;
FIG. 2 is a front view thereof;
FIG. 3 is a top plan view thereof; and,
FIG. 4 is a left side elevational view, the right side being a mirror image thereof of the present invention.
The broken lines are for illustrative purposes only and form no part of the claimed design.
